DESIGN FOR A TOY ANIMAL FIGURE

Bern Wolf, Los Angeles, Calif.

Application April 23, 1948, Serial No. 145,923

Term of patent 3½ years

(Cl. D34—15)

To all whom it may concern:

Be it known that I, Bern Wolf, a citizen of the United States and a resident of Los Angeles, Los Angeles County, California, have invented a new, original, and ornamental Design for a Toy Animal Figure, of which the following is a specification, reference being had to the accompanying drawing, forming part thereof.

I claim:

The ornamental design for a toy animal figure, substantially as shown.

BERN WOLF.
